LAMP BASE

Willie Hempstead, Los Angeles, Calif.

Application January 13, 1951, Serial No. 13,793

Term of patent 7 years

(Cl. D48—20)

To all whom it may concern:

Be it known that I, Willie Hempstead, a citizen of the United States, residing in Los Angeles, in the county of Los Angeles and State of California, have invented a new, original, and ornamental Design for a Lamp Base, of which the following is a specification, reference being had to the accompanying drawing, forming part thereof.

Fig. 1 is a top plan view of a lamp base, showing my new design.

Fig. 2 is a front elevational view thereof.

Fig. 3 is a side elevational view with the lamp socket omitted.

The dominant features of my design are shown on the drawing in full lines.

I claim:

The ornamental design for a lamp base, substantially as shown and described.

WILLIE HEMPSTEAD.
